Des. 229,218

Patented Nov. 13, 1973

229,218

COMBINED GAS LANTERN AND FUEL BOTTLE THEREFOR

Richard D. Curtis, Benjamin C. Baugh, and Robert R.
Deines, Wichita, Kans., assignors to The Coleman Com-
pany, Inc., Wichita, Kans.

Filed Dec. 23, 1971, Ser. No. 211,828

Term of patent 14 years

Int. Cl. D26—02

U.S. Cl. D48—24 R

FIG. 1

FIG. 2

FIG. 3

FIG. 4

FIG. 5

FIG. 6

FIG. 1 is a perspective view of the combined gas lantern and fuel bottle therefor showing our new design;

FIG. 2 is a side elevational view of the combined gas lantern and fuel bottle therefor of FIG. 1, the view from the opposite side being identical;

FIG. 3 is a top view of the combined gas lantern and fuel bottle therefor of FIG. 1;

FIG. 4 is a perspective view of the second embodiment of our design for a combined gas lantern and fuel bottle therefor;

FIG. 5 is a side elevational view of the combined gas lantern and fuel bottle therefor of FIG. 4, the view from the opposite side being identical; and

FIG. 6 is a top view of the combined gas lantern and fuel bottle therefor of FIG. 4.

We claim:

The ornamental design for a combined gas lantern and fuel bottle therefor, as shown and described.
